DISPLAY CARRIER AND HOLDER

Filed Jan. 25, 1933

John L. Barrett Inventor

By William Herbert Williams Attorn.
Attorn.

UNITED STATES PATENT OFFICE

JOHN L. BARRETT, OF DETROIT, MICHIGAN, ASSIGNOR TO BOHN ALUMINUM AND BRASS CORPORATION, OF DETROIT, MICHIGAN, A CORPORATION OF MICHIGAN

DISPLAY CARRIER AND HOLDER

Application filed January 25, 1933. Serial No. 653,542.

This invention relates generally to label, tag or card holders and refers more particularly to those designed for use upon the front edges of shelves or other suitable supports.

5 One of the essential objects of the invention is to provide a holder of this type which includes a trim rail or finish strip for the front edge of the shelf and a tag carrier that may be easily and quickly attached to or detached from such rail at any point longitudinally thereof.

Another object is to provide a holder wherein the rail and carrier are constructed in such a way that the carrier may be moved 15 longitudinally of the rail without being removed therefrom.

A further object is to provide a holder wherein the front face of the carrier upon which the tag or label is placed is smooth or 20 flat and is provided at its upper and lower edges with means for holding such tag or label.

A further object is to provide a holder 25 wherein the attaching means for the carrier is upon the back thereof and is preferably in the form of a struck-out lip and a spring element for engaging with the trim rail.

A further object is to provide a holder 30 wherein the spring element just mentioned is anchored beyond opposite ends of the lip and has an offset portion that is substantially parallel but is movable relative to said lip to permit the carrier to be attached to or removed from the trim rail.

35 A further object is to provide a holder wherein the spring pressure is such that the carrier will be held firmly in any adjusted position.

40 Other objects, advantages and novel details of construction of this invention will be made more apparent as this description proceeds, especially when considered in connection with the accompanying drawing, 45 wherein:

Figure 1 is a fragmentary perspective view of a shelf with a tag holder embodying my invention applied to the front edge thereof;

Figure 2 is a rear elevation of the tag carrier;

Figure 3 is a front elevation of the carrier;

Figure 4 is a vertical sectional view through the carrier;

Figure 5 is a top plan view of the carrier. 55

Referring now to the drawing, A is the trim rail and B is the carrier of a tag holder embodying my invention. As shown, the trim rail A is channel-shape and is preferably mounted upon the front edge C of a 60 suitable shelf such as D. The base 1 of the channel extends longitudinally of and is secured to the front edge C of the shelf while opposite sides 2 and 3 of the channel are provided throughout their length with inturned flanges 4 and 5, respectively, which are substantially parallel to the base 1 and spaced the same distance apart throughout their length. 65

The carrier B preferably comprises a light 70 gage sheet metal plate having a flat front face 6 upon which a tag such as 7 may be placed, and provided at its upper and lower longitudinal edges with open return bent flanges 8 and 9, respectively, for holding said tag upon said face. Projecting rearwardly from the plate at a point substantially midway of its ends is an inverted substantially L-shaped tongue or lip 11 for engagement with the lower side 3 of the channel-shaped trim rail, 75

while anchored on the back of the plate beyond opposite ends of the lip are the ends 12 and 13, respectively, of a wire spring 14 which is provided above and substantially parallel to the lip 11 with an upwardly offset portion 15 that is engageable with the upper side 2 of the trim rail. Preferably the ends 12 and 13 of the spring are return bent around and are securely held by return bent tongues 16 and 17, respectively, that are 80 struck-out from the plate. 85

Thus, in use, the carrier B with a tag such as 7 upon its front face 6 between the flanges 8 and 9 may be easily and quickly applied to the trim rail A by merely slipping the tongue 11 over the lower flange 5 so that it will engage the lower side 3 of the channel and depressing the offset portion 15 of the spring so that it will pass beneath the upper flange 4 into engagement with the upper side 2 90 95 100

of the channel, or by first slipping the offset portion 15 of the spring in rear of the upper flange 4 and then depressing it against the upper side 2 of the channel so that the tongue 5 11 may be slipped over the lower flange 5 into engagement with the lower side 3 of the channel. In either instance the carrier B may be applied at any point longitudinally of the trim rail and may, if desired, be moved 10 longitudinally of said rail after being applied without being removed. Wherever adjusted the spring will cause a firm engagement between the carrier and rail so that the tag carried thereby will be securely held in place.

15 What I claim as my invention is:

1. A tag holder including a channel-shaped trim rail, and a tag carrier attachable to said rail at any point longitudinally thereof, the attaching means for the carrier being 20 upon the back thereof and including spaced elements engageable with the opposed sides of the channel of the trim rail, one of said elements being formed of spring metal.
2. A tag holder including a channel-shaped trim rail, and a tag carrier attachable to said rail at any point longitudinally thereof, the attaching means for the carrier being upon the back thereof and including spaced elements engageable with the opposed 25 sides of the channel of the trim rail, the attaching means and rail being so formed that the carrier when attached may be moved longitudinally of the rail without being removed or detached from said rail.
3. A tag holder including a channel-shaped trim rail, and a tag carrier having a flat front face upon which a tag may be mounted, means for holding the tag upon said face, and means upon the back of the 30 carrier engageable with the channel of the trim rail for detachably securing the carrier to the trim rail at any point longitudinally thereof, the attaching means and rail being so formed that the carrier when attached 35 may be moved longitudinally of the rail without being removed therefrom.
4. A tag holder including a channel-shaped trim rail, and a tag carrier attachable to said rail at any point longitudinally thereof, the 40 attaching means for the carrier being wholly upon the back thereof and including spaced elements engageable with opposite sides of the channel-shaped trim rail, one of said elements being a struck-out part, and the other of said elements being a spring.
5. In a tag holder a tag carrier comprising a sheet of metal having a flat front face, means for holding a tag on said face, and spaced elements upon the back of the sheet 45 for detachably securing the carrier to a trim rail or other suitable support, one of said elements being struck out from said flat face, and the other of said elements being a yieldable member formed separately from but secured to the back of said sheet.

6. In a tag holder, a tag carrier comprising a plate-like member having means upon its front face for holding a tag, and spaced elements wholly upon its rear face for detachably securing the carrier to a suitable support, one of said elements being a struck-out portion substantially L-shaped in cross section, and the other of said elements being an elongated yieldable member terminally secured to said plate-like member.

7. In a tag holder, a tag carrier comprising a plate-like member having means upon its front face for holding a tag, and vertically spaced elements upon its rear face for detachably connecting the carrier to a trim rail, one of said elements being a wire spring, and the other of said elements being a projecting part of said plate-like member.

8. In a tag holder, a tag carrier comprising a plate-like member having means upon its front face for holding a tag, and provided upon its rear face with projections, and vertically spaced elements upon the rear face of said plate-like member for detachably connecting the carrier to a trim rail, one of said elements being a rearward projection of the plate-like member intermediate the spaced projections aforesaid, and the other of said elements being a separate spring having an intermediate portion thereof movable toward and away from the last mentioned projection and having other portions secured to the spaced projections.

9. In a tag holder, a tag carrier comprising a plate-like member having means upon its front face for holding a tag and provided upon its rear face with longitudinally spaced projections, and vertically spaced elements upon its rear face for detachably connecting the carrier to a trim rail, one of said elements being a rearward projection of the plate-like member intermediate the longitudinally spaced projections, and the other of said elements being a separate spring having an intermediate portion thereof substantially parallel to the last mentioned projection and movable relative thereto and having opposite ends secured to the longitudinally spaced projections.

10. In a tag holder, a plate-like member provided upon one side with spaced projections and provided intermediate said projections with a third projection, and means cooperating with the third projection for detachably connecting the member to a trim rail including a separate spring spaced from and movable relative to said third projection and having its opposite ends connected to the first mentioned projections.

11. In a tag holder, a tag carrier comprising a plate-like member having means upon its front face for holding a tag, and vertically spaced elements upon its rear face for detachably connecting the carrier to a trim rail, one of said elements being a struck-out part,

and the other of said elements being a wire spring substantially parallel to said part.

12. In a tag holder, a tag carrier comprising a plate-like member having means upon its front face for holding a tag, and means wholly upon its rear face for detachably securing the carrier to a suitable support, said last mentioned means including a struck-out part, and a wire spring having opposite ends thereof fastened to the member beyond opposite ends of the struck-out part and provided intermediate its ends in substantially vertical alignment with said struck-out part with an offset portion.

15 In testimony whereof I affix my signature.

JOHN L. BARRETT.
